(57) **CLAIM**

The ornamental design for a hot air blowing tool for melting solder, as shown and described.

DESCRIPTION

FIG. 1 is a top, front, left side perspective view of the hot air blowing tool for melting solder;

FIG. 2 is a rear, right side perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The broken lines show portions of a hot air blowing tool for melting solder which forms no part of the claimed design.
